FIG. 1

FIG. 2

INVENTOR.
PETER TAILER
BY *Leon M. Strauss*

UNITED STATES PATENT OFFICE

170,391

CLOCK OR SIMILAR ARTICLE

Peter Tailer, New York, N. Y.

Application August 20, 1952, Serial No. 21,122

Term of patent 14 years

(Cl. D42—7)

To all whom it may concern:

Be it known that I, Peter Tailer, a citizen of the United States of America and residing at New York, county and State of New York, have invented a new, original, and ornamental Design for a Clock or Similar Article, of which the following is a specification, reference being made to the accompanying drawing, forming part thereof.

Fig. 1 is a front elevational view of the clock or similar article, showing my new design;

Fig. 2 is a top plan view of the clock of Fig. 1.
I claim:

The ornamental design for a clock or similar article, substantially as shown.

PETER TAILER.
